UNITED STATES PATENT OFFICE

94,025

DESIGN FOR A DISPLAY LAMP

Howard J. Gilman and Thomas E. Mueller, Oak Park, Ill., assignors of one-third to Harry A. Norris, Philadelphia, Pa.

Application September 8, 1934, Serial No. 53,241

Term of patent 7 years

To all whom it may concern:

Be it known that we, Howard J. Gilman and Thomas E. Mueller, citizens of the United States, residing at Oak Park, in the county of Cook and State of Illinois, have invented a new, original, and ornamental Design for a Display Lamp, of which the following is a specification, reference being had to the accompanying drawing, form-

ing a part thereof, in which our display lamp is shown in elevation.

We claim:

The ornamental design for a display lamp, as shown.

THOMAS E. MUELLER.
HOWARD J. GILMAN.
